UNITED STATES PATENT OFFICE.

OSCAR E. KOHL, OF ROCHESTER, NEW YORK.

CUFF FASTENER.

1,426,571.

Specification of Letters Patent. Patented Aug. 22, 1922.

Application filed March 25, 1921. Serial No. 455,408.

To all whom it may concern:

Be it known that I, OSCAR E. KOHL, a citizen of the United States, and resident of Rochester, in the county of Monroe and 5 State of New York, have invented certain new and useful Improvements in Cuff Fasteners, of which the following is a specification.

The present invention relates to cuff fasteners and more particularly to the type in 10 which the connecting shank proceeds directly from the edges of the two heads, an object of this invention being to permit the making of one of the heads smaller than 15 the other in the cuff fastener of the type mentioned, so that the fastener may be readily introduced into the cuff, while reducing the liability of loss by the smaller head working through the cuff fastener 20 opening.

To this and other ends the invention consists of certain parts and combinations of parts, all of which will be hereinafter described, the novel features being pointed 25 out in the appended claim.

In the drawings:

Fig. 1 is a plan view of a blank from 30 which the fastener is made constructed in accordance with this invention;

Fig. 2 is an edge view of the blank;

Fig. 3 is a plan view showing the manner in which the blank may be ornamented with 35 an initial;

Fig. 4 is a section through the blank illustrated in Fig. 3;

Fig. 5 is a side view of the larger head of 40 the fastener;

Fig. 6 is a view looking at the smaller head of the fastener;

Figs. 7 and 8 are two edge views of the 45 cuff fastener;

Fig. 9 shows a fragment of a cuff from the side on which the larger head is arranged; and

Fig. 10 is a similar view on the side on 50 which the smaller head is arranged.

Prior to this invention it has been suggested to make a cuff fastener from two heads connected by a shank which proceeds 55 from the edges of the two heads so that the fastener may be made from one blank of sheet material. It has also been suggested prior to this invention to make a cuff fas-

tener from the two heads of different sizes connected by a shank which proceeds from 55 the opposite faces of the heads. The making of a construction from one piece in which the shank connects two heads, one smaller than the other is no problem of manufacture, but in use a shank construction with arms of equal length, would cause 60 the smaller head to work through the cuff fastener opening, unless such arms were made of lengths which would render the cuff fastener unsightly.

This invention makes it possible to employ heads of different sizes connected by a shank proceeding from the edges of the 65 heads without any danger of losing the cuff fastener.

Referring more particularly to the drawings and to the blanks illustrated in Figs. 1 to 4, 1 indicates the larger head which is of a size that will not readily pass through the cuff fastener opening, and 2 indicates the 70 smaller head, which is of a size adapted to be readily passed through the cuff fastener opening. These two heads are connected by a shank portion 3, the shank and the heads being preferably formed from a single piece 75 of sheet material. This material is then bent so that the shank assumes a substantially U shape with a short arm 3^a and a long arm 3^b, the short arm connecting directly with the larger head and the long arm connecting directly with the smaller head. By this arrangement, the larger head which is disposed outwardly on the cuff, has 80 one side lying substantially at one end of the cuff fastener opening as shown in Fig. 90 9, while the smaller head 2 by being carried by the longer arm is thrown away from the end of the cuff fastener opening as shown in Fig. 1. As a consequence any strains on the cuff fastener are received by the arm 3^b 95 and there is no tendency to draw the small head through the opening 4 of the cuff.

It is apparent that there has been provided a cuff fastener which may be made readily from one piece of sheet material and bent into form, one head of this cuff fastener being smaller than the other so as to facilitate its being passed readily through the cuff openings, while at the same time this head is so removed from the cuff opening that there is no tendency for the same 100 105

to be drawn through the opening in the use of the device.

What I claim as my invention and desire to secure by Letters Patent is:

5 A cuff fastener comprising two heads, one of which is smaller than the other, and a shank connecting them, formed of a U

shaped member having two arms of different lengths, the shorter arm proceeding from one edge of the larger member and the longer arm proceeding from one edge of the smaller member.

OSCAR E. KOHL.
